DESIGN FOR A LADY'S HANDBAG

Henri Felmann, Chicago, Ill., assignor to Morris, Mann & Reilly, Inc., Chicago, Ill., a corporation of Illinois

Application September 22, 1936, Serial No. 64,959

Term of patent 3½ years

To all whom it may concern:

Be it known that I, Henri Felmann, a citizen of the United States, residing at Chicago, in the county of Cook and State of Illinois, have invented a new, original, and ornamental Design for a Lady's Hand Bag, of which the following is a specification, reference being had to the accompanying drawing, forming part thereof, wherein Figure 1 is a side elevational view of a lady's hand bag showing my new design; Figure 2 is an end elevation of the same, and Figure 3 is a plan view thereof.

I claim:

The ornamental design for a lady's handbag, as shown.

HENRI FELMANN.
